HENRY B. COOLEY, OF NEW BRITAIN, CONNECTICUT, ASSIGNOR TO THE AMERICAN PAPER GOODS COMPANY, OF MONTCLAIR, NEW JERSEY, A CORPORATION OF NEW JERSEY.

DRINKING-CUP.

1,116,677.

Specification of Letters Patent. Patented Nov. 10, 1914.

Application filed February 11, 1911. Serial No. 807,990.

To all whom it may concern:

Be it known that I, HENRY B. COOLEY, a citizen of the United States, and a resident of New Britain, in the county of Hartford and State of Connecticut, have invented a new and Improved Drinking-Cup, of which the following is a specification.

My invention relates to the class of drinking vessels more generally known as sanitary cups, which are designed for individual and frequently a comparatively short use, and the object of the invention is to provide a cup of this class that may be cheaply made and that will satisfactorily withstand 15 the uses to which they may be put.

Forms of devices embodying my invention, and in the use of which the objects herein set out may be attained are illustrated in the accompanying drawings in 20 which—

Figure 1 is a view in central vertical section of one form of cup embodying my invention. Fig. 2 is a bottom view of the same. Fig. 3 is a like view showing a 25 slightly different form of construction. Fig. 4 is a view in central vertical section of the lower part of a cup embodying a still different form of construction. Fig. 5 is a detail view in section through the bottom 30 of another form of cup.

In the construction of cups of this kind it is necessary that the material should be as inexpensive as possible, and that the cup, while being comparatively light, should be 15 sufficiently strong to withstand the uses to which it may be put and also be liquid tight. I have found that a cup having a body composed of paper may be employed and that the bottom may be cheaply formed 40 in a way to provide an extremely tight and strong device of this character.

The cups herein shown and described and embodying my invention each compose a button formed of any suitable material and 45 sufficiently compact and rigid to form a strong support for the extremely thin body formed of paper and also for the binding member between which and the button the lower edge of the body is clamped to form 50 the bottom of the cup.

The paper composing the body 6 may be of the lighter thinner forms of paper having its surface treated with a suitable material to render it impervious to water. A

piece is cut to the required shape and is 55 formed into a tube larger at the top than at the bottom, as clearly shown in Fig. 1 of the drawings. The ends of this piece are secured together in any suitable manner, as by means of an adhesive, thus forming 60 a joint extending lengthwise of the cup body. The bottom edge of the cup is turned to form a lip 7 extending inwardly and a button 8, of a size to closely fit the inner part of the body at the bottom is inserted from the top and pushed into place against the lip 7, the parts thus fitting snugly together and closing the bottom of the cup against outflow of liquid that may be contained therein. 70

A binding plate 9 is placed underneath the lower edge of the body, this plate being of a size in diameter somewhat larger than the body to form a flange 10. This plate may be secured in place in any suitable manner, as herein shown pins 11 passing through the plate, through the lip 7 and through or into the button 8 being employed. This provides a bottom for the cup of sufficient size to prevent the cup from easily overturning. This button and plate may be composed of any suitable material having sufficient density and rigidity for the purpose, it having been found that paper suitably formed will accomplish the purpose, but 80 any other suitable material may be employed. 75

In the form of device shown in Fig. 3, the body 6 is constructed as herein above described and the button 12 is forced into 90 place, but in this form of cup, the lip hereinabove described is omitted. The button 12 may be slightly grooved as at 13 at its edge and a binder ring 14 of any suitable material may be employed to securely bind the thin 95 body to the button thus forming an extremely secure and strong construction. The bottom being composed of any suitable material as hereinabove described.

In the structure shown in Fig. 4 the body 10 6 is constructed as hereinbefore described and the button 8 may be of the same form as that shown in Fig. 1, being somewhat thinner, however, in this form of the device. A binding plate 15 is located outside of the 10 body and tightly binds its lower edge against the button 8. This button and binding plate may be formed of any suitable

material as above described, and in fact a suitable construction may be obtained by taking a piece of material of a size in diameter equal to that of the plate and cutting a round hole in its center of a size equal to the button 8, the part removed being the button 8 which is forced into place after the lower edge of the body 6 has been placed in the opening thus formed in the plate.

14. In the form of device shown in Fig. 5, the body 16 is formed of thin paper as hereinabove described, the cup in this figure being shown as cylindrical. The button 17 is also formed as hereinabove set out, but 15 the binding elements in this form of constriction is obtained by thickening the piece composing the body so that its lower edge will have a rib 18 of sufficient thickness to withstand the force exerted by the button 20 17, the latter being a trifle larger than the inner diameter of the body 16, so that it will be retained tightly in place. It will be obvious that this form of cup may be tapered as hereinabove described, if desired.
25. While I have shown and described herein certain forms of cup embodying my invention, I do not confine my invention to its embodiment in such form, as these may be departed from to a greater or lesser ex-

tent without departing from the spirit and intent of the invention.

I claim:—

1. A drinking cup including an open-ended body of extremely thin, flexible, collapsible material, a button composed of comparatively stiff, rigid material closely fitting within the body, and a strengthening member tightly fitting said body to clamp it to the button and hold it in place and providing a wide flange to support the cup in 43 an upright position.

2. A drinking cup including an open-ended tubular body of thin, flexible, collapsible material, a button composed of comparatively stiff, rigid material tightly fitting within the bottom, and a strengthening member consisting of a flat disk secured to the body to resist the strain exerted by the button, said disk being of a diameter much greater than the bottom of the cup and projecting beyond the sides in a plane at right angles to the axis of the cup to form a support therefor.

HENRY B. COOLEY.
